PHOTOENGRAVER'S SABER

David H. Warner and Ethel D. Warner, both of
25 E. Buddy St., Barberton, Ohio
Filed Dec. 27, 1963, Ser. No. 333,839
2 Claims. (Cl. 30—154)

This invention relates to hand tools and more particularly it pertains to a photoengraver's saber having a retractable and swingable knife blade.

Hand tools having sharp instruments which are manually movable out of a handle and automatically retractable into the handle have been known in the prior art. Most of such devices have not been suitable for use by photoengravers, artists, and the like for various reasons. Suffice it to say, a tool having a retractable knife blade which is movable into various angled positions for use outside of the handle has been developed. The skill with which the blade is used frequently depends upon the angle at which it extends from the axis of the blade handle.

It has been found that a retractable knife blade may be mounted for extension at any desired angle to accommodate the requirements of a particular purpose or of various users. The device of the present invention not only provides spring means for automatic retraction of the blade upon release of a detent, but also provides adjustable means for setting the angle of inclination of the blade.

Accordingly, it is an object of this invention to provide a photoengraver's saber having a blade which is adjustable to various angles of inclination.

It is another object of this invention to provide a photoengraver's saber having a readily adjustable knife blade which is automatically retractable into the handle of the saber.

It is another object of this invention to provide a photoengraver's saber having a cutting blade which automatically turns to the desired angle of inclination when the blade is advanced manually out of the saber handle.

Finally, it is an object of this invention to provide a photoengraver's saber which substantially eliminates the difficulties enumerated and obtains the foregoing desiderata in an effective manner.

These and other objects and advantages, apparent to those skilled in the art from the following description and claims, may be obtained, the stated results achieved, and the described difficulties overcome, by the apparatus, constructions, arrangements, combinations, subcombinations, elements, parts, and principles, which comprise the present invention, the nature of which is set forth in the foregoing general statements, a preferred embodiment of which—illustrative of the best modes in which applicants have contemplated applying the principles—is set forth in the following description and shown in the drawings, and which is particularly and distinctly pointed out and set forth in the appended claims forming part hereof.

The nature of the photoengraver's saber of the present invention may be stated in general terms as including a tubular handle having at least one open end, a plunger movably mounted within the handle near said open end, the plunger being spring-biased in a retracted position and being manually movable to an advanced position with a portion extending out of the open end, said portion of the plunger having a diametric slot, a knife blade pivotally mounted within the slot and having an outer cutting end with an inner end within the slot, a pivot pin extending perpendicularly through the slot and the knife blade, the pivot pin being disposed outside of the handle when the blade is in the advanced position, a spring within the handle, an elongated rod within the handle and having

2

one end mounted in the plunger and having another end extending toward the end of the handle remote from said open end, a body on the rod and spaced from the plunger, the spring being disposed on the rod and engageable at 5 one end with the body on the rod, stop means within the handle and adjacent the retracted plunger for engagement with the other end of the spring, the handle having an elongated bayonet slot, a manually movable button extending through the slot in the handle and having an inner end within the plunger and having an outer end extending beyond said handle slot, spring means within the plunger and engageable with the end of the blade within the plunger slot for urging the blade at an angle to the axis of the handle when the blade is in the advanced position, and the spring being compressed between the body and the stop means when the blade is in the advanced position.

In the drawings:

FIGURE 1 is a plan view of the photoengraver's saber;

FIG. 2 is a vertical sectional view through the saber showing the blade in the retracted position;

FIG. 3 is a similar view through the handle showing the blade in the extended position;

FIG. 4 is a transverse sectional view taken on the line 20 4—4 of FIG. 2; and

FIG. 5 is a transverse sectional view taken on the line 25 5—5, FIG. 3.

Similar numerals refer to similar parts throughout the several views of the drawings.

In the drawings a knife or saber is generally indicated at 1. It includes an elongated tubular member or tube 2, a retractable knife blade 3, a coil spring 4, and blade advancing means or button 5 for extending the blade out of the tube. The tube 2 is provided with an end closure member 6. The other end 7 is open to permit extension and retraction of the blade 3.

As shown in FIGS. 2 and 3 the inner wall of the tube 2 has two portions 8 and 9 of different diameter, the former having a smaller diameter than the latter. An annular radial shoulder 10 is provided therebetween. In addition the end portion of the tube 2 having the smaller inner diameter is provided with a longitudinally extending slot 11 having a back-turned end portion or notch 12 in which the button 5 is secured during extension of the blade 3.

The knife blade 3 includes a cutting end 13 and an inner end portion 14. The blade is apertured at 15 for reception of a pivot pin 16. As shown in the drawings a plunger member 17 is slidably mounted within the inner tube portion 8 and has a yoke or bifurcated end portion 18 which provides a slot 19 in which the inner end portion 14 of the blade 3 is seated. The pivot pin 16 extends through the slot 19 and the blade aperture 15 with pin end portions mounted in the opposite sides of the yoke 18.

As shown in the drawings the plunger member 17 includes a lower bore 29 and an upper threaded bore 21, both of which bores extend between the end of the slot 19 and the end of the plunger member 17 remote from said slot. A blade-turning unit is mounted in the bore 20 and includes a compressed coil spring 22, a slideable plunger 23, and a spring-backup plug 24. The plunger 23 extends into the slot 19 in contact with a portion 25 of the inner end of the knife blade 3. Thus, the spring 22 exerts a constant rotating force on the blade 3 in a clockwise direction about the pivot pin 16.

An elongated rod 26 extends from the plunger member 17 throughout a greater portion of the tube 2. A threaded end portion 27 of the rod 26 is seated in the threaded bore 21 and extends into the slot 19 for contact with another portion 28 of the inner end of the blade 3. The opposite end of the rod 26 is slotted at 29 so that a screw driver

may be used for turning the rod to adjust the angle of inclination of the blade 3.

As shown more particularly in FIG. 5 the button 5 includes an inner shaft portion 30 which is seated at 31 within the plunger member 17. The shaft 30 extends upwardly through the slot 11 and the outer end button 5 protrudes outside of the outer surface of the tube where it is conveniently available for contact.

As shown in the drawings the coil spring 4 is disposed between the shoulder 10 and a member 32. In the extended position of the spring (FIG. 2) the blade 3 is retracted within the tube 1. In the compressed position of the spring (FIG. 3), the blade 3 is extended for use. The member 32 is provided with a threaded aperture 33 which is attached to a threaded portion 34 of the rod 26. The member 32 is preferably round with a diameter slightly smaller than that of the inner tube portion 9. The right end of the spring 4 presses against the member 32 and the left end of the spring presses against the shoulder 10 and a partition member 35 is preferably provided between the spring and the shoulder 10.

As viewed in FIGS. 2 and 3 the right end portion of the rod 26 extends through a block 36 which by a pin 37 is secured within the inner tube portion 9. A rubber or resilient pad 38 is provided on the left end of the block 36. Both block 36 and pad 38 are provided with aligned apertures 39 through which the rod 26 extends. Similarly, the end closure member 6 is provided with an aperture 40 which is aligned with apertures 39 and which is an access opening for insertion of a screw driver into the slot 29 at the end of the rod 26.

In operation, when the blade 3 is retracted within the tube 2 (FIG. 2), the cutting end 13 is completely seated within the open end 7 and the button 5 is disposed at the extreme right end of the slot 11. At the same time the spring 22 acts through the plunger 23 and presses against the inner end portion 25 of the blade 3 to urge the edge of the blade against the inner tube portion 8 at 41.

The blade is advanced to the extended position (FIG. 3) by pushing the button 5 to the left in the slot 11 and turning the button into the notch 12 for holding the blade in said position. During that moment the coil spring 4 is compressed by the member 32 moving with the rod 26. In the extended position, the pivot pin 16 is disposed just outside of the open end 7 of the tube 2 where the blade is free to rotate in response to the thrust of the spring 22 until the end portion 28 is brought into contact with the end of the rod 27. The angle of inclination of the blade 3 may be adjusted by rotating the rod 26 so that a greater or lesser portion of the threaded end portion 27 extends into the slot 19 thereby changing the degree of rotation of the blade.

The compression of the spring 4 may be adjusted by rotation of the rod so that the threaded portion 34 advances or moves the member 23 to the right or left as desired.

In the preferred position of the member 32, the member is in contact with the pad 38. Accordingly, when the button 5 is released from the notch 12 to permit the plate to return from the advanced position (FIG. 3) to the retracted position (FIG. 2), release of the button in the slot 11 permits the spring 4 to rapidly pull the blade into the tube. At the end of the motion the member 32 strikes the resilient pad 38 and thereby dampens the shock and noise resulting from retraction of the blade 3.

In the foregoing description certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful construction, and reasonable mechanical equivalents thereof obvious to those skilled in the art, are set forth in the appended claims.

What is claimed is:

1. A photoengraver's saber including a tubular handle having at least one open end, a plunger movably mounted within the handle near said open end; a spring within the handle for holding the plunger in a retracted position, the plunger being manually movable to an advanced position with a portion extending out of the open end, said portion of the plunger having a diametric slot, a knife blade pivotally mounted within the slot and having an outer cutting end with an inner end within the slot, the pivot pin being disposed outside of the handle when the blade is in the advanced position, an elongated rod within the handle and having one end mounted in the plunger and having another end extending toward the end of the handle remote from said open end, a body on the rod and spaced from the plunger, the spring being disposed on the rod and engageable at one end with the body on the rod, stop means within the handle and adjacent the retracted plunger for engagement with the other end of the spring, the handle having an elongated bayonet groove, a manually movable button extending through the groove in the handle and having an inner end within the plunger and having an outer end extending beyond said groove, spring means within the plunger and engageable with the end of the blade within the slot for urging the blade at an angle to the axis of the handle when the blade is in the advanced position, the spring being compressed between the body and the stop means when the blade is in the advanced position, and the end of the rod within the plunger engaging the inner end of the blade in its angled position.

2. A photoengraver's saber having a tubular handle with an open end, a plunger within the handle and being manually movable from a retracted position within the handle to an extended position at the open end of the handle, a spring within the handle and holding the plunger in the retracted position, the plunger having a slot in the end adjacent the handle open end, a knife blade being pivotally mounted within the slot, a pivot pin extending through the slot and the knife blade, the knife blade having an outer cutting end and having an end within the slot, the pivot pin being outside of the open end of the handle when the plunger is in the advanced position, an elongated rod within the handle and having one end mounted in the plunger and having a body mounted on the rod and spaced from the plunger, the spring having stop means within the handle adjacent the plunger and the other end of the spring being engageable with said body, the spring being compressed when the plunger is in the advanced position, means within the plunger for rotating the blade at an angle and including spring means operable against the inner end of the blade for thrusting the blade about the pivot pin at an angle to the axis of the handle, and the end portion of the rod within the plunger engaging the inner end of the blade at its angled position.
